SHEET METAL WORKING MACHINE

Herbert L. Johnson, Peabody, Mass.

Application March 10, 1945, Serial No. 582,098

10 Claims. (Cl. 153—26)

(Granted under the act of March 3, 1883, as amended April 30, 1928; 370 O. G. 757)

1

This invention relates to sheet metal working machines and is illustrated herein as embodied in a machine for forming a flange at one or more margins of a flat blank.

Joints are commonly made in duct work by joining with a gasket between them, two disk like members each having a flange to which the duct sections to be joined are fitted. Such flanged members are commonly made from an annular blank, the inner margin of which is bent at a right angle to the web of the blank, the diameter of the flanged portion of the blank being such as to permit it to fit closely within the duct. One machine for making flanged members of this type is disclosed in U. S. Patent No. 2,370,666 issued to Herbert L. Johnson on March 6, 1945.

In my prior machine, the work is fed by two driven rolls and the flanging is done by a non-driven rotatable tool which is moved radially of the upper roll to form a flange about the latter. One object of the present invention is to provide an improved and simplified machine of this type. Accordingly, in the illustrated machine the feeding of the blank and also the forming of a flange are effected by only two instrumentalities, an anvil having end and side surfaces, and a flanging tool, the anvil and tool both being rotatable and driven. As herein illustrated, the tool is mounted for movement axially thereof and is arranged to hold the blank in driving engagement with the end surface of the anvil, as well as to form the flange about the anvil. Since the tool and anvil are driven at the same peripheral speed, no drag is exerted against the work by the flanging tool. Thus a positive and regular feed movement is insured, and at the same time, distortion of the work and any tendency for it to jam in the guiding means is eliminated.

A certain amount of bending of the flange beyond its desired position may be necessary, as the flange is being formed, to insure that the flange will finally stand at the desired angle from the web. The work-engaging members of a flanging machine may be constructed and arranged properly to form a flange on material of one thickness or kind; but the same machine may not be adapted for forming a flange at the desired angle to the web when operating on material of another thickness or kind, unless it includes provision for altering the relation between the work-engaging members in accordance with the new conditions.

Accordingly, the invention in another aspect includes the provision of an adjustment for both the anvil and the flanging tool in the present machine by which, while maintaining the proper

2

operative relation between the anvil and tool, their angular relation with respect to the plane of the web of the blank may be varied. Hence, a flange may be formed at an exact right angle to the web, regardless of the resiliency of the material employed. Moreover, the flange may also be formed at an angle to the web which is slightly acute or obtuse if in so doing the fit between the flange and the duct section to be joined therewith would be improved.

Other instances of the use of flanged members call for the forming of the flanges on the outer margins of the blanks. For example, such flanged members may be used as caps to close 15 the end of a duct section, or may become the ends of tanks.

The illustrated machine is adapted for doing this type of work, owing to the provision therein, as another feature of the invention, of means for swinging the anvil and tool angularly in opposite directions to such an extent as to reverse their relative position with respect to the axis of the blank. In this instance a blank can not be guided by its outer periphery since the flange is formed at that location. Accordingly, when an external flange is formed on a blank by the use of the illustrated machine, the guiding of the blank is effected by a pivot constituting, in combination with the flanging instrumentalities, another feature of the invention. As herein illustrated, the pivot is adapted to engage the blank at its center and, to be fixed in any position of adjustment radially of the anvil and tool in accordance with the desired height of the flange and the size of the blank being operated upon.

With the above and other objects and features in view, the invention will now be described with reference to the accompanying drawings which illustrate a preferred embodiment of the invention and will be pointed out in the claims.

In the drawings:

Fig. 1 is a view in front elevation of an illustrative machine embodying the invention;

Fig. 2 is a plan view showing the tables, parts 45 of the machine above it being broken away, and illustrating the guiding of the blank in a flanging operation;

Fig. 3 is a sectional plan view showing the flanging tool and its operating means, the section being taken slightly below the level of the table;

Fig. 4 is a sectional front elevation illustrating the mounting and arrangement of the anvil and flanging tool, and their relation to a blank when a flange is formed on an internal margin thereof;

Fig. 5 is a fragmentary sectional view of one

of the guides, the section being taken along the line 5—5 of Fig. 2;

Fig. 6 is a sectional elevation illustrating the flanging of the outer margin of a blank and the guiding of the blank in such an operation.

The illustrated machine comprises a base 10 (Fig. 1), of welded H-beam construction, to one end of which is fixed a pedestal 12 adapted to support one end of a table 14. The other end of the table is fixed to an arm 16, integral with the base 10, and arranged to extend above and centrally over the left-hand end of the table. A bracket 18, having a slide-way in which a slide 20 may be adjusted vertically, is mounted for angular adjustment on a pivot 22 fixed to the arm 16, for a purpose to be explained later. This adjustment is made by turning a hand wheel 23 which drives a gear 24 arranged to mesh with a gear segment 25 formed in the bracket 18. The hand wheel and gear 24 are fixed to a shaft rotatably mounted in the arm 16. Upon completing the adjustment of the bracket 18, it is clamped in position by setting up bolts 26 which pass through arcuate slots in the bracket and are threaded into the arm 16.

Fixed to the slide 20 (Fig. 4) is a housing 21, in which a shaft 28 is mounted to rotate on roller bearings 29 and 30. The lower end of the shaft 28 has the form of a truncated pyramid and is adapted to be received in a similarly squared recess in an anvil 31 which is secured to the shaft by a screw 32. The anvil 31 has frusto-conical end and side surfaces, the former being knurled to insure a positive feeding action.

The anvil 31 is adjusted into proximity to a blank or workpiece on the table 14 by turning a lever 34 carried by a shaft 36, the latter being mounted to rotate in the bracket 18. A pinion 38, fixed to the shaft 36, is arranged to mesh with a rack cut in the slide 20, the latter thus being moved heightwise when the lever 34 is operated. The slide 20 may be locked to the bracket 18 by setting up a clamp 40 having a shank threaded in the bracket 18, and adapted to bear against the slide 20. The blank is supported directly underneath the anvil 31 by a block 41 (Fig. 4) and a roll 42 which is mounted to rotate freely in the block. The block is adapted to be turned end for end and to be adjusted lengthwise of the table, as illustrated in Figs. 4 and 6, in a slideway formed at the sides of an opening 43 in the table 14.

The shaft 28 is driven by an electric motor 44 (Fig. 1) which is mounted on the top of the bracket 18, through connections comprising a worm 45 fixed to the motor-shaft and a worm gear 46. The gear 46 and the shaft 28 are splined to provide a driving connection therebetween regardless of the adjustment of the slide 20 heightwise of the table 14.

A power-driven rotary, and axially movable flanging tool 48, and the anvil 31, cooperate, as will be more fully pointed out below, to impart a feed movement to the workpiece and also to form a flange thereon as indicated in Fig. 4.

The flanging tool 48 has a frusto-conical side surface, a rounded end surface, as clearly illustrated in Fig. 4, and is secured to the upper squared end of a shaft 50 by a screw 52. The shaft 50 is mounted to rotate in a sleeve 54 on roller bearings 56 and 58, the sleeve being arranged to slide vertically in a housing 60. A rubber shield 61 arranged to cover the upper end of the sleeve prevents scale and dirt from entering the bearing 56 and from falling on the side of the sleeve 54. The housing 60 is arranged to slide

lengthwise of the machine in a slideway 62 on a carriage 64, and the latter is arranged to tilt in a vertical plane about a shaft 66, carried by a boss 68 fixed to the frame 10.

The flanging tool 48 is driven in rotation by an electric motor 70 (Fig. 3) which is mounted on a bracket 72 fixed to the housing 60. A driving connection between the motor and the flanging tool is provided by a worm 74, fixed to the motor shaft, and a worm gear 76 splined to the shaft 50, the gear being rotatably mounted in the housing 60 as shown in Fig. 4. The flanging tool 48 is moved axially by turning a hand-wheel 78 (Fig. 3), which is rotatably mounted in a bracket 80, fixed to the housing 60. The hand-wheel 78 is fixed to a shaft 82 which carries a gear 84 arranged to mesh with another gear 86, formed on the right-hand end of a worm 88. The worm and gear 86 are mounted to rotate in the housing 60. A shaft 90, also mounted to rotate in the housing 60, has on one end a worm gear 92, arranged to mesh with the worm 88. On the other end of the shaft 90 is fixed a pinion 94 (Fig. 4) which meshes with a rack cut in the side of the sleeve 54. Thus, by means of the connections above described, when the hand-wheel 78 is turned, the sleeve 54 and the flanging tool 48 may be raised or lowered as desired.

The position of the flanging tool 48 may be adjusted radially of the anvil 31 by either an angular or rectilinear movement of the tool. The latter adjustment is effected by turning another hand-wheel 96, which is carried by a shaft 98, the latter being rotatably mounted on a bracket 100 fixed to the carriage 64. A threaded shaft 102 rotatably mounted on the carriage 64 has fixed to its right-hand end a gear 104 adapted to mesh with another gear 106, the latter being fixed to the shaft 98. The shaft 102 is threaded into a plate 108 (Fig. 4) which is secured to the base of the housing 60 and accordingly, when the shaft 102 is rotated, the housing 60 is moved lengthwise of the machine in the slide-way 62.

Angular adjustment of the flanging tool 48 radially of the anvil 31 is effected by turning a hand-wheel 110 (Fig. 3) which is fixed to a shaft 112, the latter being rotatably mounted in bracket 114, extending from the left-hand end of the carriage 64. A gear 116, fixed to the shaft 112, is arranged to mesh with another gear 118, which is mounted to rotate on a yoke 120, the latter being pivoted at 122 to the bracket 114. The gear 118 is internally threaded to receive a screw 124 (Fig. 4) which is pivoted at 126 to a boss 128 fixed to the frame 10. It is now apparent that by turning the hand-wheel 110, the gear 118 may be moved up or down on the screw 124, and that a corresponding tilting movement is imparted to the carriage 64.

A blank to be flanged is located and guided properly with respect to the anvil 31 and flanging tool 48, as will be more fully pointed out later, by a guide comprising rolls 130 and 132 (Fig. 2), which are rotatably mounted on arms 134 and 136 respectively and are adapted to be engaged by the periphery of the blank.

The arms 134 and 136 are pivoted at 138 and 140 respectively, to a plate 142, having holes which slidably receive bolts 144 (Fig. 1), threaded at their lower ends into a block 146. The block is dove-tailed in cross section and is adapted to fit within, and slide lengthwise of the table 14, in a similarly shaped groove 148 in the middle of the top of the table. The guide may thus be positioned at any location lengthwise of the table in

order to determine the width of the margin of the blank to be flanged. The guide is fixed in such position by tightening a clamp 150, the shank of which is threaded into a bar 152 through the bolts 144 also extend. When the clamp 150 is tightened, it presses downward against the plate 142, and thus forces the arms 134 and 136 against the table. Similarly, the bar 152 is raised and by lifting the bolts 144, causes the block 146 to be wedged tightly in the groove 143, whereby the guide is locked to the table. Adjustment of the rolls 130 and 132 laterally of each other, in order to accommodate blanks of widely varying diameters, is effected by adjusting a turn buckle 153 (Fig. 2), the threaded shanks of which are pivoted at 154 and 155 to the arms 134 and 136 respectively. The arms are further provided with segmental gears which insure that the rolls will always be at equal distances from the center line of the table.

The guide is so located lengthwise of the table that when a blank is in engagement with the rolls 130 and 132, as illustrated in Fig. 2, the portion of the blank which is to form the flange is to the right of the anvil 31 and over the flanging tool 48; the latter, at the beginning of a flanging operation, being in the recess 43 and below the top of the table. The blank is constantly held against the rolls 130 and 132 by another pair of rolls 158 and 160, the latter rolls being mounted on arms 162 and 163 respectively. These arms are adapted to be adjusted with respect to each other and to be clamped to the table in the same manner as that employed in connection with the arms 134 and 136 described above. The construction of the roll 160 will now be described in detail with reference to Fig. 5, it being understood that each of the other rolls 130, 132, and 158 is of the same construction:

The roll comprises a sleeve 164, the outer side of which is threaded to receive a collar 165 adapted to be adjusted vertically on the sleeve in order to accommodate blanks of varying thicknesses. The sleeve 164 is attached by a press fit to the outer race 166 of a ball bearing, the inner race 168 of which is pressed onto a stud 170. The arm 163 is bored to receive the stud, the latter being threaded and held on the arm by a nut 172. To assist the operator in adjusting the collar 165, he may insert a temporary locking bar 174 into aligned holes in the arm 163 and the sleeve 164, whereby rotation of the latter is prevented when the collar 165 is rotated. The collar is secured in adjusted position on the sleeve by a set screw 175, the inner end of which engages the threaded portion of the sleeve 164.

The operation and adjustment of the machine will now be described with reference to the forming of a flange on an internal margin of an annular blank, it being assumed first that the flange is to be formed at substantially a right angle to the web of the blank.

The bracket 18 is first adjusted angularly about the pivot 22 so that the portion of the side surface of the anvil 31 nearest to the flanging tool 48 (the latter being to the right of the anvil as illustrated in Fig. 4) is either vertical or is inclined at an angle which is slightly acute with respect to the web portion of the blank. This adjustment is made by turning the hand-wheel 23 and setting up the bolts 26. The position of the anvil 31 heightwise of the table is next adjusted by operating the lever 34, thereby lowering the slide 20 to a point where the anvil 31 bears lightly on the blank. The guide rolls 130, 132, 158, and

160 are now adjusted so that the blank is centered with reference to the groove 143, and so that the inner circumference of the blank is spaced to the right of the anvil 31 by an amount substantially equal to the desired height of the flange to be formed. It is noted that the guide roll means prevents any translational movement of the blank and yet permits rotational movement thereof. The flanging tool 48, which at this time is just below the blank, is next adjusted, by operating the hand-wheel 110, so that its axis is either vertical or inclined slightly toward the position in which it is illustrated in Fig. 4. The flanging tool is also adjusted lengthwise of the machine, by operating the hand-wheel 96, to such a position that when the tool is elevated, it will be spaced from the anvil 31 by a distance substantially equal to the thickness of the blank. Assuming now that the motors 10 and 44 are operating, the handwheel 78 is turned to bring the flanging tool 48 into contact with the lower surface of the blank. At this stage, the feeding movement of the blank begins, the blank being held by the flanging tool against the knurled end surface of the anvil 31, throughout the flanging operation. The hand-wheel 78 is further operated to raise the flanging tool 48, which, as illustrated in Fig. 4, progressively bends the inner margin of the blank about the lower edge of the anvil 31 towards, or into contact with, its side surface. The flanging operation can be thus carried out, on most types of material, by a single upward movement of the flanging tool when it is adjusted as described above. In this situation, the flanging action occurs for the most part, at the upper rounded surface of the flanging tool, there ordinarily being a slight clearance between the side surface of the flanging tool and the inside surface of the flange. If necessary, however, the flanging tool 48 can be readjusted toward the end of the flanging operation by further tilting the flanging tool into the position in which it is illustrated in Fig. 4, this adjustment being accompanied by a slight movement of the flanging tool to the left, effected by turning the hand-wheel 96. Accordingly, as illustrated in Fig. 4, under the conditions of the adjustment last described, the anvil 31 and the flanging tool 48 will have line contact with the flange on opposite sides thereof throughout its height. When the flanging operation is completed, the flanging tool 48 is first moved to the right by operating the hand-wheel 96 and then is lowered below the top of the table to permit a new blank to be placed thereon.

When a flange is to be formed on the outer margin of a blank, the anvil 31 and the flanging tool 48 are angularly adjusted to positions in which their relation is the reverse of that illustrated in Fig. 4. That is, the flanging tool is to the left of the anvil, as illustrated in Fig. 6. Otherwise, the tool and anvil are operated as described above. In this case however, the guide rolls referred to above can not be used since it is the margin of the blank which is flanged. Accordingly the blank is guided by a pivot 176 (Fig. 6) adapted to be seated in a punch mark, or a small hole (as herein illustrated) in the center of the blank. It is apparent that the pivot 176 may be made large enough to fit within a central opening of any size in a blank. Hence, the machine is adapted for guiding annular blanks of the type illustrated in Fig. 4, as well as the solid circular type illustrated in Fig. 6, in connection with an external flanging operation. The pivot 176 is rotatably mounted on a ball bearing 178.

the inner race of the latter being attached to a screw 180 which is threaded into an arm 182. The arm is mounted to slide lengthwise of the machine on the lower flange of a beam 184 which is bored at its right-hand end to receive the pedestal 12. A collar 186 which may be clamped to the pedestal 12, is adapted to support the beam at a convenient height above the table and to permit the beam to be swung out of the way when not in use. When a blank has been centered and located on the table properly, the beam 184 and arm 182 are moved to align the pivot 176 with the punch mark or hole in the blank. The screw 180 is next turned to bring the pivot into register with the mark or hole. The pivot is then fixed in this position by securing the arm 182 to the beam 184 and also by securing the latter to the pedestal 12. To this end, a set screw 188 is threaded in the arm 182 and is adapted to be seated against the lower flange of the beam 184, whereby the arm 182 is clamped to the beam. The beam is similarly locked to the pedestal by tightening bolts 190.

The blank is prevented from buckling away from the table by the use of one or more guides of the type illustrated in Fig. 6, each guide comprising a caster 192 mounted to roll on the blank just inside of the base of the flange. The guide comprises a base 194 which is clamped by a bolt 196 to the table 14 outside of the area of the table covered by the blank. On one pair of arms (one of which is indicated at 198) extending horizontally from the base 194, is pivoted a link 200, having a hole adapted to receive the shank 202 of the caster 192. The link 200 is slotted to receive a nut 204, threaded on the shank 202, and which is adapted on being turned to adjust the caster 192 heightwise of the table. The caster is adapted to be swung upwardly above the finished flange to facilitate the removal of the work from the machine, and is thus operated by swinging a bell crank 206 in a clockwise direction. The bell crank is pivotally mounted at 208 on the base 194. The lower arm of the bell crank 206 is pivoted to one end of a toggle link 210, the other end of which is pivoted to a lug extending upwardly from the link 200.

The illustrated machine may be converted into a rotary shearing machine by substituting for the flanging tool 48 a sharp edged tool similar to the anvil 31. In adjusting the machine for a shearing operation, the anvil and shearing tool are positioned with their edges substantially tangent to each other, the anvil and tool being angularly adjusted so that elements of their side surfaces at the point of tangency are aligned and perpendicular to the top of the table 14.

The invention described herein may be manufactured and used by or for the Government of the United States of America for Government purposes without the payment of any royalty thereon or therefor.

Having described my invention what I claim as novel and desire to protect by Letters Patent of the United States is:

1. A flanging machine comprising a table, an anvil having an end surface and a frusto-conical side surface, a flanging tool, means for angularly adjusting said anvil to permit its being positioned with either of two opposite elements of its conical side surface substantially perpendicular to said table, means for adjusting said tool radially of said anvil whereby said tool can be brought into operative relation to said anvil adjacent to either

of said elements of its side surface, a block mounted on said table directly below said tool roller having an axis of rotation parallel to said table mounted at one end of said block, said block being positioned on said table with said roller in cooperative relationship with said anvil and said tool for supporting a blank, means for rotating said anvil and tool, means for moving said tool axially in proximity to the side surface of said anvil, thereby simultaneously to hold said blank in driving engagement with the end and side surfaces of said anvil and to bend a margin of the blank about said anvil, and means for holding said blank against translational movement while in driving engagement.

2. A machine for flanging a marginal portion of the inner periphery of an annular blank, said machine comprising an anvil and a flanging tool, means associated therewith for adjusting said anvil and tool into engagement with the opposite faces of the blank and in offset relation with respect to the marginal portion thereof, means for rotating said anvil and tool to impart rotative feed movement to the blank, a block mounted in the proximity of the point of engagement of said anvil and said tool, a roller rotatably mounted in said block in cooperative relationship with said anvil and said tool for supporting the portion of said blank adjacent said marginal portion, guide means adjustable to engage the periphery of the blank to hold the same against translational movement but permitting said rotative feed movement, a section of the adjusting means associated with the tool being operable to advance the tool toward the marginal portion to bend said portion against the anvil.

3. A machine for flanging the internal periphery of an annular blank according to claim 2 wherein said guide means includes a plurality of rolls engageable simultaneously with the periphery of the blank and an adjacent portion of at least one of its faces.

4. In a machine for flanging the internal periphery of annular blanks, an anvil, a flanging tool, each having end and side faces, means for adjusting said anvil and tool so that their side faces lie in offset relation with respect to a marginal portion of a blank and their end faces engage the opposite faces of the blank, means for driving said anvil and tool in rotation to impart a rotative feed movement to said blank, a block mounted in the proximity of said anvil, a roller rotatably mounted in said block in cooperative relationship with said anvil and said flanging tool for supporting said blank on the face thereof engaged by said anvil, roll means adjustable into peripheral engagement with said blank for guidingly holding the blank against translational movement during its rotation, a part of the adjusting means for said tool being operable to move the tool against the marginal portion to progressively bend said portion against said anvil.

5. In a flanging machine, in combination, an anvil, a flanging tool, said anvil and tool being supported for engagement with opposite faces of an annular blank on opposite sides of the inner boundary of a marginal portion thereof, means for rotating said anvil and tool to impart a rotative feed movement to said blank, a block mounted in the proximity of said anvil, a roller rotatably mounted in said block in cooperative relationship with said anvil and said flanging tool for supporting said blank on the face thereof engaged by said anvil, means for engaging said blank to hold it

against translational movement, means for moving said anvil and tool relatively to each other transversely of the plane of the blank, and means to reverse the relative positions of said anvil and tool with respect to the rotation axis of the blank, whereby a flange can be formed progressively about said anvil on either an internal or an external margin of the blank.

6. A machine for flanging the inner periphery of an annular blank, said machine comprising a table, an anvil, a flanging tool, a block adjustably mounted in the proximity of said anvil, a roller rotatably mounted in said block in cooperative relationship with said anvil and said flanging tool for supporting said blank, means for driving said anvil and said tool in rotation to impart a feed movement to said annular blank when disposed therebetween, means for moving said tool transversely to the plane of said blank, thereby to bend a margin of the blank about said anvil, and guide rolls mounted on said table peripherally to engage and hold said blank against translational movement during its feed movement.

7. A machine for flanging the inner periphery of an annular blank, said machine comprising a table, an anvil, a flanging tool, means for rotating said anvil and tool to impart a rotative movement to said blank positioned therebetween, said anvil and said tool being supported for engagement with opposite faces of said blank on opposite sides of the inner boundary of a marginal portion thereof, a block adjustably mounted on said table in the proximity of said anvil, a roller rotatably mounted in said block in cooperative relationship with said anvil and said flanging tool for supporting said blank near said inner boundary, guiding means constructed and arranged to maintain a constant relation between said inner boundary and said anvil and tool, and means for moving said tool axially while the blank is rotated to bend said marginal portion progressively into engagement with said anvil, and means for adjusting said anvil with respect to the plane of the blank whereby the angle between the flange and the faces of the blank may be varied.

8. A machine for flanging a periphery of a blank, said machine comprising, a table, an anvil having an end surface and a frustro-conical side surface, a flanging tool, means for angularly adjusting said anvil to permit its being positioned

with either of two opposite elements of its side surface substantially perpendicular to said table, means for adjusting said flanging tool radially of said anvil whereby said tool can be brought into operative relation to said anvil adjacent to either of said elements of its side surface, a block adjustably mounted in the proximity of said anvil, a roller rotatably mounted in said block in cooperative relationship with said anvil and said tool for supporting said blank, means for rotating said anvil and tool, means for moving said tool, axially in proximity to the side surfaces of said anvil, thereby simultaneously to hold said blank in driving engagement with the end and side surfaces of said anvil and to bend a margin of said blank about said anvil, and means for holding said blank against translational movement while in driving engagement.

9. A machine for flanging the external periphery of a circular blank, said machine comprising the apparatus of claim 8 wherein said last mentioned means comprises a pivot supported on an arm and adapted to engage said blank at its center, said arm being attached to and extending over said table, whereby said blank is caused to rotate about a fixed axis while in driving engagement.

10. A machine for flanging the internal periphery of an annular blank, said machine comprising the apparatus of claim 8 wherein said last mentioned means includes a plurality of rollers adjustably mounted on said table, said rolls being engageable simultaneously with the outer periphery of said blank and an adjacent portion of at least one of its faces.

HERBERT L. JOHNSON.
